Horace Vincent Rodgers-Bannister, London, England, assignor to Modern Telephones Corporation, New York, N. Y.

Application November 9, 1950, Serial No. 12,916
In Great Britain June 16, 1950

Term of patent 7 years

(Cl. D26—14)

To all whom it may concern:

Be it known that I, Horace Vincent Rodgers-Bannister, a subject of the King of England and resident of 101, Tottenham Court Road, London, W. 1., England, have invented a new, original, and ornamental Design for a Transducer Housing, of which the following is a specification, reference being had to the accompanying drawings, forming part thereof.

Figure 1 is a front perspective view of a transducer housing showing my new design.

Figure 2 is a side view.

Figure 3 is an end view.

Figure 4 is a view of the opposite side to that of Figure 2 and

Figure 5 is a view of the base.

I claim:

The ornamental design for a transducer housing, substantially as shown.

HORACE VINCENT
RODGERS-BANNISTER.
